DESIGN FOR A PLATE

Karl Bayreuther, Selb, Germany, assignor to The
Rosenthal China Corporation, New York, N. Y.,
a corporation of New York

Application September 25, 1935, Serial No. 58,704

Term of patent 14 years

To all whom it may concern:

Be it known that I, Karl Bayreuther, a citizen of Germany, residing at Selb, Bavaria, Germany, have invented a new, original, and ornamental Design for a Plate, of which the following is a specification, reference being had to the accompanying drawing, forming a part thereof.

Fig. 1 of the drawing is a top plan view of

a plate showing my new design; and Fig. 2 is a side view showing the plate of Fig. 1 partly in elevation and partly in section.

I claim:

The ornamental design for a plate, as shown and described.

KARL BAYREUTHER.
